ABSTRACT OF THE DISCLOSURE

The extension table comprises a hollow, transverse, vertical central support having aligned pairs of parallel longitudinal slots at its upper and lower ends. The lower slots receive therethrough, parallel tubular longitudinal floor engaging members. Received in the upper pair of slots are a pair of parallel, longitudinal, horizontal tubes. Tie rods passing through said hollow central support connect the upper tubes to the lower tubular members. Mounted on the upper tubes is a table top. Slidable in said upper tubes are extension members which may be extended to support extension leaves disposed in the plane of the table top and located at the ends thereof. The table top may be removably mounted on the upper tubes by means of small plastic friction discs. Said upper pair of tubes are formed at their undersides and adjacent their outer ends with openings registering with hollow finger grip portions in said extensions so that the operator may insert a finger through said opening to start the outward movement of the extension. Spacers are attached to the undersides of the extension leaves for engagement with the sliding extension members. Means is provided to limit the outward movement of the extension members.

BRIEF SUMMARY OF THE INVENTION

This invention relates to tables. An object of the invention is to provide a table having extension leaves and which may readily be put together or taken apart for shipment or storage.

Another object of this invention is to provide a highly improved extension table in which a central, transverse, hollow support receives floor engaging members at its lower end and table top supporting members at its upper end.

Still another object of this invention is to provide an extension table of the character described in which the upper table top supporting members comprise tubes which slidably house extension members which may be pulled out or retracted. In the pulled out position the extensions may support extension leaves. The table top is removably supported on the upper tubes by means of plastic friction means which keep the table from accidentally moving but which allow the table top to be lifted off. The upper and lower members are interconnected by means of tie rod passing through the hollow, central, transverse support.

A still further object of this invention is to provide in an extension table of the character described, improved means to permit the extensions to be manually pushed out and in which means is further provided to hold the extension leaves in the plane of the table top and non-slidably mounted on the extension members.

Yet another object of this invention is to provide a strong, rugged and durable extension table which is inexpensive to manufacture, attractive in appearance, easy to manipulate, easy to knock down and store and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction

2

hereinafter described, and of which the scope of invention will be indicated in the following claims.

BRIEF DESCRIPTION OF THE SEVERAL VIEWS OF THE DRAWING

5 In the accompanying drawing, in which is shown an illustrative embodiment of this invention,

FIG. 1 is a perspective view of an extension table embodying the invention and showing the extension leaves in place;

10 FIG. 2 is a cross-sectional view taken on line 2—2 of FIG. 1;

FIG. 3 is a bottom plan view of the table;

FIG. 4 is a cross-sectional view taken on line 4—4 of FIG. 1;

15 FIG. 5 is a cross-sectional view taken on line 5—5 of FIG. 1;

FIG. 6 is a perspective, expanded view illustrating the mounting of an extension leaf on the table;

20 FIG. 7 is a partial bottom plan view of one of the extension members and a portion of the table top adjacent thereto;

FIG. 8 is a cross-sectional view taken on line 8—8 of FIG. 2;

25 FIG. 9 is a cross-sectional view taken on line 9—9 of FIG. 8; and

FIG. 10 is a combined cross-sectional and perspective view illustrating the structure shown in FIG. 9.

DETAIL DESCRIPTION OF THE INVENTION

30 Referring now in detail to the drawing, 10 designates an extension table embodying the invention. The same comprises a hollow, transverse, central vertical support 11. The support 11 may have parallel, opposed, vertical walls 12 interconnected by parallel vertical, side walls 13. Between walls 12 and 13 is a horizontal bottom wall 14 and a horizontal top wall 15. The walls 12 and 14 are formed with a pair of lower, vertical slots 16 and said walls 12 and 15 are formed with a pair of upper, vertical slots 17. Slots 16 and 17 are in vertical alignment.

35 40 Another object of this invention is to provide a highly improved extension table in which a central, transverse, hollow support receives floor engaging members at its lower end and table top supporting members at its upper end.

45 Still another object of this invention is to provide an extension table of the character described in which the upper table top supporting members comprise tubes which slidably house extension members which may be pulled out or retracted. In the pulled out position the extensions may support extension leaves. The table top is removably supported on the upper tubes by means of plastic friction means which keep the table from accidentally moving but which allow the table top to be lifted off. The upper and lower members are interconnected by means of tie rod passing through the hollow, central, transverse support.

50 55 A still further object of this invention is to provide in an extension table of the character described, improved means to permit the extensions to be manually pushed out and in which means is further provided to hold the extension leaves in the plane of the table top and non-slidably mounted on the extension members.

60 65 Yet another object of this invention is to provide a strong, rugged and durable extension table which is inexpensive to manufacture, attractive in appearance, easy to manipulate, easy to knock down and store and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction

side walls 40c of the tubes 40 and the side walls 13. Blocks 8 may be interposed between the ends of walls 43 and the undersides of walls 47. Wall 43 has openings 50 aligned with the openings 27. The lower walls 40a of tubes 40 are formed with opening 51 registering with the openings 0. Inside of each upper tube 40 and resting on the lower side wall 40a is a metal plate 60 disposed centrally above the transverse hollow support 11. Plate 60 is attached to the lower tube wall 40a by means of screws 61. Said plate 0 is formed with a pair of threaded openings 62 registering with openings 63 in the bottom wall 40a, which openings register with the openings 50 in wall 43.

Tie rods 64 pass through the openings 31, 29, 28, 27, 0, 63 and 62. The upper ends of the tie rods 64 are threaded and are screwed into the threaded opening 62. The lower ends of the tie rods 64 are screw threaded and nuts 52 screwed thereto contact the underside of the plate 0. Thus the tubes 18 and the boards 19 are firmly connected to the central support 11 and to the upper tubes 40.

Said upper tubes 40 extend to opposite sides beyond the lower tubes 18. The lower tubes 18 may be supported on rollers 70 which contact the floor. The casters 70 are preferably connected to the outer ends of the tubes 18. The tubes 18 are coextensive with the wooden board 19, as shown in FIG. 2. The tubes 18 extend equal distances to opposite sides of the central support 11. The tubes 40 also extend equal distances to opposite sides of the central support 11. The tubes 18 and 40 are located closer to the side walls 13 than to the middle of the transverse support 11. Adjustable glides may be used instead of rollers 70.

For the purpose hereinafter appearing, the bottom walls 40a of the upper tubes 40 are formed adjacent the outer ends thereof with openings 73. The openings 73 may be oval, round or of any other suitable shape.

Attached to the ends of the walls 40a, and spaced inwardly of the openings 73 are upstanding stop pins 74 for the purpose hereinafter appearing.

Slidable in each of the outer ends of the upper tubes 40 are parallel extension members 75. When the extension members are moved inwardly toward each other they will contact opposite side edges 60a of the plate 60. When said extension members 75 are wholly within the tubes 40, the outer ends 46 are located substantially at the ends of said tubes. Said extension members 75 are rectangular in cross-section, the same as the tubes 40. Said extension members 75 are formed at their undersides with longitudinal slots 78 terminating short of the ends thereof.

The pins 74 project upwardly into the grooves 78. When the extension members 75 are pulled all the way out, the pins 74 serve as stops engaging the inner ends of grooves 78 to limit outward movement. At the outer ends of the grooves 78 are enlarged spaces 79 each terminating in an end inner abutment surface 80. When the extension members 75 are wholly within the tubes, the spaces 79 are disposed above the opening 73. To pull the extension members outwardly, the operator inserts a finger upwardly through an opening 73, engages the abutment surface 80 at the outer end of the groove and pushes the extension member sufficiently outwardly so that it may be gripped from the outer end and pulled out.

A table top 90 having a width preferably greater than the central support 11 may be mounted on the upper tubes 40 by means of soft plastic discs 91 attached to the top walls 40b of the tubes, adjacent the outer ends thereof. The discs 91 may be made of vinyl or nylon and are preferably soft and frictionally engage the underside of the table top.

The table top 90 may be made of glass or any other suitable material.

The table may be used without any extension leaves and in such event the extension members 75 remain within the tubes 40. However, the extension leaves 95 may be employed to increase the length of the table. Each extension leaf 95 is preferably a rectangle and of the thickness of the table top 90 and also of the width thereof.

Attached to the underside of each extension leaf 95 adjacent the outer end is a spacer member 96. Each member 96 has a top wall 97 screwed or otherwise attached to the underside of the extension leaf and an end flange 98 to engage the outer edge 96 of the extension 75 and side flanges 99 engaging the side surfaces of the extension 75. Extending downwardly from the top wall 97 is a pin 100 which may engage in a socket or bore 101 in the extension 75. The pin 100 thus locates the extension 95 in proper place and also spaces the extension leaf above the extension 75 and in the plane of the table top 90.

Spacing members 103 are attached to the undersides of the extension leaves 95. It will be noted that the table top extends a short distance beyond the outer ends of the tubes 40. The members 103 are attached to the inner ends of the extension leaves 95 and each has a top wall 104 screwed or otherwise attached to the underside of the extension leaf, and side flanges 105 contacting the side surfaces of the extension member 75. Members 103 also have inward reduced projections 106 which engage beneath the table top and these are of a thickness somewhat greater than the thickness of the upper walls 40b of tubes 40. Thus members 96 and 103 serve to retain the extension leaves 95 in the plane of the table top.

It will thus be seen that there is provided an article in which the several objects of this invention are achieved, and which is well adapted to meet the conditions of practical use.

As possible embodiments might be made of the above invention, and as various changes might be made in the embodiment above set forth, it is to be understood that all matter herein set forth or shown in the accompanying drawings, is to be interpreted as illustrative and not in a limiting sense.

I claim:

1. A table comprising a vertical, transverse support, a pair of lower parallel longitudinal floor engaging members at the lower end of said support, a pair of upper longitudinal table top supporting members at the upper end of said support, means to attach said longitudinal members to said support, and a table top removably mounted on said table top supporting members, said support having upwardly opening slots at its upper end receiving middle portions of said upper longitudinal members, and having downwardly opening slots in its lower end receiving middle portions of said lower longitudinal members, said support being hollow, said means for attaching said longitudinal members to said support comprising tie members passing vertically through said support, said upper longitudinal members comprising tubes, said upper tubes being open at their outer ends, extension members slidable in said upper tubes and extensible outwardly therefrom, and extension leaves removably mounted on said extension members and located at the opposite ends of said table top.

2. The combination of claim 1, said table top being liftable upwardly off said upper longitudinal members, and friction members on said upper longitudinal members engaging the underside of said table top.

3. The combination of claim 1, and means to limit outward movement of said extension members.

4. The combination of claim 1, and means on said extension members to retain said extension leaves in the plane of said table top.

5. The combination of claim 4, and means to prevent horizontal movement of said extension leaves relative to said extension members.

6. A table comprising a vertical, transverse, central support, a pair of lower parallel longitudinal floor engaging members at the lower end of said support and extending to opposite sides of said support, a pair of upper longitudinal table top supporting members at the upper end of said support and extending to opposite sides of said support, means to attach said lower and upper longitudinal members to said support, and a table top mounted

on said table top supporting members and extending to opposite sides of said central support, said central support extending across the major portion of said table top, and said table top extending longitudinally of said upper and lower members, longitudinal extension members slidably mounted on said table top supporting members, and extension leaves removably mounted on said extension members and located in the plane of said table top and contacting the ends of said table top.

7. The combination of claim 6, means to limit outward sliding movement of said extension members relative to said table top supporting members.

8. A table comprising a vertical, transverse, central support, a pair of lower parallel longitudinal floor engaging members at the lower end of said support and extending to opposite sides of said support, a pair of upper longitudinal table tops supporting members at the upper end of said support and extending to opposite sides of said support, means to attach said lower and upper longitudinal members to said support, and a table top mounted on said table top supporting members and extending to opposite sides of said central support, said central support extending across the major portion of said table top, and said table top extending longitudinally of said upper and lower members, said upper longitudinal members comprising tubes open at their outer ends, extension members slidable in said tubes and extensible outwardly through said outer open ends of said tubes, and extension leaves removably mounted on said extension members and located at the opposite ends of said table top, said tubes having openings adjacent their outer ends, and said extension members having shoulder means adjacent their outer ends accessible to said openings, so that a finger inserted in the openings can engage said shoulder means to slide the extension members relative to said tubes.

9. A table comprising a vertical, transverse support, a pair of lower parallel longitudinal floor engaging members at the lower end of said support, a pair of upper longitudinal table top supporting members at the upper end of said support, means to attach said longitudinal members to said support, and a table top removably mounted on said table top supporting members, said upper longitudinal members comprising tubes open at their outer ends, extension members slidable in said tubes and extensible outwardly through said outer open ends of said tubes, and extension leaves removably mounted on said extension members and located at the opposite ends of said table top, said tubes having openings adjacent their outer ends, and said extension members having shoulder means adjacent their outer ends accessible to said openings, so that a finger inserted in the openings can engage said shoulder means to slide the extension members rela-

tive to said tubes, said extension members having longitudinal slots, and means on said tubes to engage within said slots to limit sliding movement of said extension members relative to said tubes.

5 10. A table comprising a vertical, transverse, central support, a pair of lower parallel longitudinal floor engaging members at the lower end of said support and extending to opposite sides of said support, a pair of upper longitudinal table top supporting members at the upper end of said support and extending to opposite sides of said support, means to attach said lower and upper longitudinal members to said support, and a table top mounted on said table top supporting members and extending to opposite sides of said central support, said central support extending across the major portion of said table top, and said table top extending longitudinally of said upper and lower members, said upper longitudinal members comprising tubes, said upper tubes being open at their outer ends, extension members slidable in said upper tubes and extensible outwardly therefrom, and extension leaves removably mounted on said extension members and located at the opposite ends of said table top.

15 20 25 11. The combination of claim 10, said support having upwardly opening slots at its upper end receiving middle portions of said upper longitudinal members, and having downwardly opening slots at its lower end receiving middle portions of said lower longitudinal members.

20 25 30 12. The combination of claim 10, said support being hollow, said means for attaching said longitudinal members to said support comprising tie members passing vertically through said support.
